UNITED STATES PATENT OFFICE.

JOHN J. REDKEY, OF DENVER, COLORADO.

RAILROAD-TIE.

1,108,396.

Specification of Letters Patent. Patented Aug. 25, 1914.

Application filed July 18, 1913. Serial No. 779,787.

To all whom it may concern:

Be it known that I, JOHN J. REDKEY, a citizen of the United States, residing at Denver, in the county of Denver and State 5 of Colorado, have invented certain new and useful Improvements in Railroad-Ties; and I do hereby declare the following to be a full, clear, and exact description of the invention, such as will enable others skilled 10 in the art to which it appertains to make and use the same.

This invention relates to new and useful improvements in railroad ties and has for its object the provision of a tie to which 15 the rail is adapted to be secured and which will be practically indestructible.

Another object of my invention is the provision of a fastening means which may be easily and quickly adjusted to eliminate 20 kinks in laying the rail.

Another object of my invention is the provision of a device of the above character which will firmly and securely hold the rails in their position and also which will permit of easy removal of the same when it is desired to replace such rails.

Still another object of my invention is the provision of a tie to which a rail brace may be easily and quickly applied when it is desired to use the same on curves and the like.

With the above and other objects in view I now proceed to describe my invention in the following specification and accompanying drawings, in which,

Figure 1 is a view of one end of my improved tie showing the same as it would appear with the rail in place. Fig. 2 is an end view in elevation of my improved railroad tie, Fig. 3 is a fragmentary elevational view of my improved tie showing the rail receiving recess in detail, Fig. 4 is a top plan view of Fig. 1, Fig. 5 is a bottom view of a fragment of my tie, Fig. 6 is a plan view of the blank from which my improved tie is made, Fig. 7 is a view of a nut used in connection with the locking means, and Fig. 8 is a detail fragmentary view of one of the clamping plates showing the grooves by means of which the nut is prevented from rotating. Fig. 9 is an enlarged detail sectional view of the rail brace showing the same in position and clearly illustrating the locking tooth.

Referring to the drawings by characters 55 of reference 1 indicates generally my improved railroad tie preferably comprising a

bottom 2, the sides 3, and the end portions 4. Adjacent each end of the tie and in the top edges of the sides I preferably form the recesses 5, the lower walls forming these recesses being preferably flared outwardly, as shown at 6, to form seats upon which my improved rail fastening means is adapted to rest. Intermediate the ends of the tie and the recesses I preferably form the notches 7 which are so positioned as to form a shoulder 8, the use of which will be more fully hereinafter described.

My improved rail fastening means preferably comprises the two plates, indicated 70 generally by the numeral 9, having formed integrally at their ends the depending ears 10. This depending ear 10 is preferably provided with an aperture 11 through which a suitable bolt is adapted to pass by means 75 of which the same is pivotally connected to the tie. An upstanding rib 12 is formed along the lateral edges of the plate and provided at its upper extremity with the in-turned flange engaging portion 13. At each 80 end of the plate I preferably provide the wedge portions 14 which extend outwardly from the upstanding member and by means of which the position of the rail held in the clamping plates may be adjusted with relation to the coöoperating rail at the opposite 85 end of the tie.

A suitable transversely extending bolt 15 passes through the aperture 11 formed in the depending ear 10 and also through the 90 aperture 16 formed in the tie immediately beneath the recess 5 and adjacent to one end thereof. A second aperture 17 is formed in the tie at the end of the recess opposite the shouldered aperture 16 and is adapted to receive the end 18 formed on the bolt 15. The end of the bolt opposite the head is preferably screw threaded and provided with a nut 19 having formed in one face thereof the grooves 20, which are adapted to receive one 100 end of the coil spring 21 and be held from revolving through frictional engagement with said spring. The opposite end of the coil spring 21 is extended as clearly shown and presses into the recesses 22 formed in 105 the outer face of the depending ear 10. Thus it will be seen that the spring will be held from rotation when the device is in use.

The under side of the tie as will be clearly seen upon referring to Fig. 5 is provided 110 with the diagonally extending ribs 23 which are adapted to be engaged by the road bed

and thus hold the tie from accidental movement. When it is desired to use my improved metallic tie in connection with railroads having automatic electric signals I 5 preferably enlarge the recesses in the clamping plates and insert a suitable insulator, indicated by the numeral 24 which may be of fiber or any non-conducting material which it is desired to use.

- 10 The improved rail brace which I use in connection with my metallic tie preferably comprises the upstanding body portion 25 which is preferably bifurcated at its lower extremity and enlarged, as clearly illustrated at 26. A suitable tooth 27 is formed integral with the body portion at the inner extremity of the bifurcation and is adapted to engage the shoulder 8 formed by the notches 7 in the upstanding member of the 15 tie. The end of the body portion 25 opposite the enlarged portion 26 is extended as clearly illustrated at 28 and provided with the rail engaging surfaces 29 and 30, which are adapted to engage the under surface of 20 the head of the rail and the web of the rail respectively.

It will be clearly seen from the foregoing when my improved tie is in use the plates are placed in position on the tie and the bolts 30 passed through the apertures formed in the depending ears and the upstanding portions of the tie. These plates are then swung upwardly on their respective pivots and the rail lowered into engagement with the 35 plates. It will be seen that upon further lowering of the rail the plates may be forced downwardly and the flange engaging members 13 will overlie a portion of the flange of the rail and hold the same in place.

40 Should it be desired to true up the rail with

relation to the coacting rail and remove kinks therefrom the user will tap the ends of the plates and cause the wedge members 14 to engage the end walls of the recesses, thereby causing the rail to slide longitudinally with relation to the tie and thus bring about the desired result. A suitable space is provided in my improved rail tie to permit the rail to expand as the heat affects the same.

45 While in the foregoing I have shown and described the preferred embodiment of my invention, I wish it to be understood that I may change the specific arrangements of parts without in any way departing from 50 the spirit and scope of my invention.

55 What I claim is:—

In combination with a metallic tie comprising a base portion, upstanding members formed at the lateral extremities of the base 60 portion, said upstanding members having recesses adjacent their ends and apertures immediately beneath the recesses, flared portion formed on the lower wall of the recesses, clamping plates, depending ears 65 formed integral with said clamping plates having apertures therein, flange engaging members formed at the lateral extremities of the clamping plates, bolts adapted to extend through the recesses of the ears and the recesses in the tie, springs surrounding the bolts at their threaded ends, and nuts threaded on the ends of the bolts and forming abutments for the ends of the springs.

70 In testimony whereof I affix my signature 75 in presence of two witnesses.

JOHN J. REDKEY.
